UNITED STATES PATENT OFFICE

151,108

DESIGN FOR A CRACKER TRAY

John W. Verduyn and Lewis M. Mason, Long Beach, Calif.; said Mason assignor to said Verduyn

Application February 24, 1947, Serial No. 137,140

Term of patent 14 years

(Cl. D44—14)

To all whom it may concern:

Be it known that we, John W. Verduyn and Lewis M. Mason, citizens of the United States, residing at 820 Cedar Avenue, Long Beach 2, and 240 The Toledo, Long Beach 3, in the county of Los Angeles and State of California, respectively, have invented a new, original, and ornamental Design for Cracker Tray, of which the following is a specification, reference being had to the accompanying drawing, forming a part thereof.

Figure 1 is a top plan view of our cracker tray. Figure 2 is a side elevation of the same.

We claim:

The ornamental design for a cracker tray, as shown.

JOHN W. VERDUYN.
LEWIS M. MASON.
